UNITED STATES PATENT OFFICE.

MAX BERKOWITZ, OF LAWRENCE, NEW YORK

HAND BAG.

Application filed June 28, 1924. Serial No. 722,461.

To all whom it may concern:

Be it known that I, MAX BERKOWITZ, a citizen of the United States, residing at Lawrence, in the county of Nassau and State of New York, have invented certain new and useful Improvements in Hand Bags, of which the following is a specification.

This invention relates to improvements in hand bags and more particularly to improvements in ladies' hand bags of the flat type.

A particular object of the invention is the provision of a hand bag which will be usable by its owner with and will match costumes of various colors.

Another object of the invention is the provision of a reversible hand bag in which various shades or colors of materials may be employed and on the exterior of which the material of the shade or color desired, may be exposed at the will of the user.

Further objects of the invention will be apparent from the drawings in which

Fig. 1 is a perspective view of the hand bag of my improved invention shown partly opened.

Fig. 2 is a perspective view of the same hand bag having a different colored material exteriorly exposed.

Fig. 3 is a longitudinal section of the hand bag in an extended open position.

Fig. 4 is a vertical section of the hand bag closed.

Fig. 5 is an enlarged sectional view of the clasp used in the hand bag.

Fig. 6 is an enlarged horizontal view of the clasp showing the manner in which it is affixed to the bag.

A represents the body of the bag shown in Fig. 3 in the fully extended position and in Figs. 1 and 2 in the partially bent position. This body A consists throughout its length of facings of materials of dissimilar colors on the two sides thereof. In this embodiment a facing of black silk is shown at B in the drawing and a facing of red leather is shown at C. At the point D the facings of the body portion A are separated to form the separate flaps E and F an intermediate partition K forms the usual expandable pockets formed by the bellows folds G and H having side walls of the usual type.

A portion of the body A marked O in the drawing (see Fig. 3) is bendable over the pockets formed by said bellows folds H and G in either direction and is secured in place

by the clasp m which has a swivel connection with the body of the bag so that the ornamental side of the clasp m may always be exposed to view. The clasp m has a snap fastener m' which is detachably held in the sockets R and R' (see Figs. 3 and 4). The tabs S and S' serve for the purpose of locking the body of the bag to the pockets thereof as shown in Figs. 1 and 2, these tabs S and S' having fasteners on the inside thereof engaging with the socket members T and T' when the tab S is in an exposed position on the exterior of the bag as shown in Fig. 4. The tab S or S' can be used as a holder for a handkerchief or for a similar purpose.

In the making of this improved bag, it will be evident that the differently colored facings B and C are extended uniformly through the entire length of the bag on each side. The side walls of folds G and H may however, be made of materials having colors corresponding respectively to the colors of the flaps E or F as normally these pockets are not exposed when the bag is closed.

I am aware that previous attempts have been made to make reversible hand bags of the ordinary pocket type of an oval or circular form, but I believe it is new to construct a flat hand bag which is reversible, of the type herein disclosed.

If the person using the bag desires to have the facing B upon the outside thereof, then the body portion A is bent downwardly in the position shown in Figure 3. The clasp m which is located at what may be called the free end of the body portion A is turned about its swivel so that the fastener member m' is upon the under side of the bag. When the fastener member m' is caused to engage in the socket R the bag is completely closed.

By keeping the fastener m in the position shown in Figure 3 and by bending it upwardly until the member m' engages the socket R', the facing C is exposed so as to give the appearance of an entirely different bag having an entirely different color. Each of the facings B and C is made for this purpose of what is called in the trade "outside material", that is, finished material in distinction to lining material.

It is understood that various modifications may be made from the construction herein illustrated such as, varying the number of pockets and the form of the fasteners, with-

out departing from the spirit of my invention.

Having thus fully described my invention, what I claim is:

- 5 1. A reversible hand bag composed of two opposed members constituting a flap, said flap having at one end thereof an outwardly opening pocket, the flap being foldable on either side of the pocket and constituting a closure therefor in either position, the flap and pocket when in unfolded condition having a different contrasting finish on opposite sides thereof.
- 10 2. A reversible hand bag composed of a member constituting a flap, said flap having at one end thereof an outwardly opening pocket, the flap being foldable on either side of the pocket and constituting a closure therefor in either position, the flap and pocket when in unfolded condition having a different contrasting finish on opposite sides thereof and cooperable means on said flap and pocket for holding said parts in closed relation in either position.
- 15 3. A reversible hand bag composed of a member constituting a flap, said flap having at one end thereof an outwardly opening pocket, the flap being foldable on either side of the pocket and constituting a closure therefor in either position, the flap and pocket when in unfolded condition having a different contrasting finish on opposite sides thereof and carrying means mounted on one side of the flap to serve as a handle when said flap is in closed position.
- 20 4. As a new article of manufacture, a reversible hand bag comprising two opposed members of contrasting finish on opposite sides, one serving as an outer exposed surface to the bag in one condition and the other serving as an outer surface in the re-

verse condition, the two members being connected along three sides thereof with the fourth side disconnected and open, there being a pocket between said open sides, the said two members being readily bendable at such point in converting the bag from one face outward to bring the said face inward and a carrying member adjacent the fold which covers the mouth of the pocket.

45 5. A hand bag having a body portion formed of a plurality of pieces of material of contrasting finish on opposite sides, the said body portion having a free end and having the said pieces of material separated at the other end thereof to form separate flaps, a partition member located intermediate said separated flaps and connected therewith, members connected to said partition member and to each of said flaps so as to 55 form pockets, the pieces of material forming said body portion being freely bendable about the said pocket in both directions so as to expose both sides thereof, the said body portion being of sufficient length to 60 provide a cover member to close the open end of said pocket.

6. A hand bag comprising a pocket portion, a substantially flat two-ply body portion continuous thereof with opposite faces 70 of different contrasting finish, the said body portion being bendable about the said pocket portion in both directions and being of sufficient length to include a cover member adapted to be bent over the mouth of the 75 said pocket portion, and handles located on said body portion adjacent the base of said cover member.

In testimony whereof I hereunto affix my signature.

MAX BERKOWITZ.
